(57) **CLAIM**

The ornamental design for a wall rack for bicycle, as shown and described.

DESCRIPTION

FIG. 1 is a perspective view of a wall rack for bicycle showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view showing the present invention shown in use; and,

FIG. 9 is another perspective view showing the present invention in an alternate configuration.

The broken lines shown illustrate environment that form no part of the claimed design.
